E. J. WAY,
REEL FOR CINEMATOGRAPH FILM AND THE LIKE,
APPLICATION FILED MAY 23, 1921.

1,432,647.

Patented Oct. 17, 1922.

UNITED STATES PATENT OFFICE.

EDWARD JOHN WAY, OF JOHANNESBURG, TRANSVAAL, SOUTH AFRICA.

REEL FOR CINEMATOGRAPH FILM AND THE LIKE.

Application filed May 23, 1921. Serial No. 471,838.

To all whom it may concern:

Be it known that EDWARD JOHN WAY, a British subject, residing at 134 Cullinan Building, Simmonds Street, Johannesburg, Transvaal, Province of the Union of South Africa, has invented certain new and useful Improvements in Reels for Cinematograph Film and the like, of which the following is a specification.

10 The present invention has reference to reels for holding cinematograph film and the like, the object of the invention being the provision of a simple and effective form of reel constructed to be disassembled to remove the film coil therefrom or to place it in position, having a collapsible core and an automatically releasing grip for the end of the film.

20 The invention is illustrated in the accompanying drawings in which

Fig. I is a side view of the reel with the front cheek removed and the core collapsed.

Fig. II is a section through A—A Fig. III, showing the core expanded.

25 Fig. III is a cross section through B—B Fig. II, and

Fig. IV shows the inner face of the front cheek.

1 indicates the front cheek and 2 the back cheek of the reel. The core consists of several segments 3 of a disc, each segment being slotted at 4 to slide on pins 5 fixed to the cheek 2. Centrally the core is formed with a conical bore 6, and centrally on the inner face of the front cheek 1 is fixed a similar cone 7.

At each side of the cone project wings 8 and the spaces 9 between the core segments are wide enough to permit said wings 8 to pass between them. The edges 10 of the wings are bevelled to facilitate their entrance into said spaces 9.

The gripping device for the film end consists of a spring 11 fixed in a shallow recess 45 12 in one of the segments 3 and overlapping a similar recess 13 in the next segment.

In use the reel is assembled on its driving shaft 14 where it is secured and its parts held together by any suitable means, such as

the clip 15. The cone 7 enters the bore 6 of the core as shown in Fig. III and expands the core to its full size. The wings 8 enter any opposite pair of the spaces 9 between the core segments and thus provide a positive rotational driving means causing the whole reel to rotate together upon the shaft 13 being rotated.

The spring 11 is so shaped that when the core is thus expanded said spring presses on the surface of the recess 13. The film is clipped to the reel by lifting the spring 11 with the finger, inserting the film end beneath it and allowing the spring to close on said end. After the film is wound, the clip 15 is released and the front cheek 1 is withdrawn. This permits the segments 3 to collapse and at the same time relieves the pressure between the spring 11 and the surface 13, so permitting the film coil to be freely withdrawn from the reel. In the same way a detached coil may be placed on the reel when the front cheek is removed, although in this case it would not usually be necessary to grip the end of the film. Upon then placing the front cheek 1 in position the core 3 is expanded and holds the coil firmly in place.

I claim:

1. A reel for cinematograph film and the like consisting of two cheeks, core segments attached to one cheek to slide radially thereof, a cone on the other cheek to enter and expand said segments, and wings on the cone to enter the spaces between the segments.

2. A reel for cinematograph film and the like consisting of two cheeks, core segments attached to one cheek to slide radially thereof, a spring secured at one end to one such core segment, the other end of said spring being free and adapted when the core is expanded to overlap and press on the next core segment, whereby the end of a film may be held between said free end of the spring and said next core segment, and means on the other cheek for expanding the core.

In testimony whereof I hereunto affix my signature.

EDWARD JOHN WAY.
